THOMAS JOHANCEN AND EDWARD KEHOE, OF BALTIMORE, MARYLAND.

MEANS FOR ATTACHING ROLLS OF PAPER TO SPINDLES.

Application filed August 13, 1926. Serial No. 129,100.

This invention relates to improved means for attaching rolls of paper to spindles and is particularly directed to an improved device for quickly securing rolls of print paper on spindles or shafts for use in cylinder presses, such as are used in newspaper establishments.

Rolls of print paper are wound on tubes or cores of heavy paper or iron, which tubes or cores remain a part of the roll until the paper is run therefrom and passed through the press.

Before placing the rolls in position on the press, it is the practice to first mount them on a spindle or shaft and then lift the spindle or shaft with the roll mounted thereon and seat the shaft or spindle-ends in bearings on the press-frame so the roll and spindle may be revolved as the paper is wound and fed through the press.

Considerable difficulty is experienced at times in mounting the rolls on the spindles because it is a common practice to drive wedges between the ends of the tubes or cores and the spindles which is slow and unsatisfactory and frequently results in the roll being eccentrically mounted with the result that when unwinding intermittent jerks are given to the web and the latter tears, thus interrupting the printing operation until the web can be rethreaded through the press.

In practice, two forms of tubes or cores are employed in these paper rolls,—one being a heavy paper tube with metal ferrules on the ends thereof and the other being a metal tube.

Our invention therefore has for its object to provide an improved device for quickly and accurately securing the cores, either paper or metal, to spindles whereby the rolls may revolve evenly and without subjecting the web of paper to the strains that have heretofore caused the paper to tear because of the eccentric revolution of the same.

The invention is illustrated in the accompanying drawings wherein,—

Fig. 1. shows a longitudinal sectional detail through a paper core—the paper roll thereon being indicated by broken lines, and also shows the spindle extending through the core and locked in place by our improved device.

Fig. 2. illustrates a similar view but with a tubular metal core, and with our improved device connecting the core with the spindle.

Fig. 3. shows in perspective one end of a paper core having the metal ferrule thereon.

Fig. 4. illustrates, also in perspective, one end of a metal core.

Fig. 5. shows our detached device in side elevation.

Fig. 6. illustrates an inner end view of the same.

Fig. 7. illustrates the same in outer end elevation.

Fig. 8. shows the detached device in top or plan view, and

Fig. 9. shows an enlarged vertical sectional detail through the engaged parts as the same would appear if viewed on the line 9—9 of Fig. 1.

Referring to the drawings the numeral 10, designates a paper roll which is wound on a central tubular core 11, which core may be of paper or metal.

In the structure disclosed in Figs. 1 and 3 of the drawings, the tubular core 11 has a metal ferrule 12 at each of its ends for reinforcement purposes, and in said form the interior of each ferrule has a keyway or recess 13 therein as clearly shown in Fig. 3.

In the structure illustrated in Figs. 2 and 4 of the drawing, the tubular core is presumed to be formed of metal 14, and the ends of this metal tube are provided with notches 15.

It is immaterial to our invention which of these cores is employed in the paper rolls as our structure is designed to coat with either of them in locking the core and the paper roll it carries to the spindle.

Our improved device, detached from the spindle and paper roll, is illustrated in Figs. 5 to 8 inclusive of the drawings to which particular attention is directed.

The structure includes a conical body 16 which extends laterally from a circular head 17 and both the body and head being provided with a circular opening or passage of 100 a diameter to snugly receive the spindle or shaft 18.

The smaller inner end 19 of the conical body 16 is of a smaller diameter than the interior diameter of the core-end 12 of core 11 or the end of the core 14, whichever core

happens to be in use, while the taper of the body is such that its circumference will wedge into the core-end, as shown in Figs. 1 and 2 of the drawings.

8. A key-slot 20 is formed in the head and conical body which slot extends through the head but is closed circumferentially at its outer end by the head but is open at both outer and inner circumferential sides of the 10 conical body. The inner end of the slot is closed at 21 as best shown in Fig. 8 of the drawing.

A set bolt 22 is provided in the head 17 so as to extend therethrough and into the 15 key-slot while another set-bolt 23 extends also through the head to the longitudinal passage.

A key 24 is provided which latter is designed to fit the slot 20 and is of sufficient 20 length to extend through the head and to the rear end of said slot.

In the present instance the key 24 is rectangular in cross-section and is straight from end to end and when inserted in the slot 20, 25 its inner or rear end will project outwardly from the slot or radially with respect to the axis of the conical body.

To mount a roll and its core on the spindle 18, the latter is passed through the 30 core and a conical body 16 is inserted on each of the projecting ends of the spindle,—the smaller end 19 of the body is then entered in the core 11 or 14, and when doing this the body is turned so that the key- 35 slot 20 therein will register with the recess 13 or the notch 15 in the end of the core.

The tapered body is then wedged or driven into the core-end sufficiently to engage the same without slipping and this operation 40 centers the spindle in the core.

The keys 24, are then slipped into the key-slots 20 from the outer side and pushed inwardly through said heads until their inner ends enter the recesses 13 or notches 15 45 whereby to lock the bodies and the cores together. The set screws 22 may then be turned down through the heads so as to lock the keys in place while the set screws 23 may also be turned to lock the bodies to the 50 spindles.

The structure is exceedingly simple and easily operated and will readily center the spindles in the cores.

The entire device,—spindle, core and roll, 55 is then lifted into place on the press and the web of paper from the roll fed through the press in the usual way.

Having described our invention, we claim,—

60 1. In a device for securing the cores of paper rolls to spindles which cores have notches or key-ways in their ends, the combination with a continuous one-piece conical body having a rigid head at the larger end 65 thereof and provided with a central passage

therethrough of a diameter to fit the spindle on which it is to be mounted,—said conical body having a radial slot that extends all the way through it from the central passage outwardly,—the inner end of said slot being 70 closed adjacent to but spaced from the small end of the conical body and the outer deepest end of the slot registering with a groove which extends horizontally through the rigid head which groove is in communication 75 with the central passage through the head—a key extending from the outer side of the head through the groove in the head into the radial but closed-end slot,—said key having its inner end extending radially from the radial slot of the cone-body and entering the notches in the cores with the outermost flat face of the key beneath the innermost wrap of the paper on the core and means for securing the body to a spindle. 80

2. The combination with a paper roll having a tubular core which latter has a notch in the edge at each end thereof, of a spindle extending through the core and projecting at each end thereof, a conical body having an enlarged head at the larger outer end thereof and a central passage therethrough which fits the spindle said conical body having a slot which opens radially from the inner side face of the enlarged head and which extends all the way through the conical body from the spindle passage outwardly,—the head portion having a groove portion extending from its outer side face through said central passage in horizontal alinement with the said slot, a key extending horizontally through the groove of the head and projecting through the slot of the conical body to the outer side of the latter whereby to enter the end notch in the core when the conical body is entered into said core to lock the conical body and core together and means extending through the enlarged head to engage the spindle to lock the conical body and spindle together. 95

3. The combination with a roll of paper, of a core extending through the center of the roll, a spindle extending all the way through the core but of a lesser diameter than said core, two devices for centering and locking the core and roll of paper on the spindle,—each of said devices comprising a body having a continuous head at the outer side and a conical portion at its inner side, the inner end of the conical portion being closed circumferentially but both the head and the conical portion being provided with a central passage that fits the spindle snugly,—the conical portion having a longitudinal slot that extends from the circumferentially-closed end thereof to the head which slot opens radially through the said conical portion and the head having a key-way extending therethrough from the outer side to and in register with the radial slot in the conical por- 100 105 110 115 120 125 130

tion,—the cone-ends of the two devices being entered in the ends of the core to center the latter about the spindle, and keys insertable from the outer side of the head through the key way in each head said keys having their inner ends extending radially through the slots of the co-portion of the bodies and

said inner ends of the keys engaging the ends of the cores to lock the same to the bodies and the spindles.

10

In testimony whereof we affix our signatures.

THOMAS JOHANCEN.
EDWARD KEHOE.
